DESIGN FOR A CUP HANGER

William Katz, Detroit, Mich., assignor to Evelyn Lowe, Joseph H. Jones, Frances Emery, and William Katz, co-partners doing business under the firm name of Kitchen King Products Company, Detroit, Mich.

Application September 24, 1945, Serial No. 122,279

Term of patent 14 years

(Cl. D44—29)

To all whom it may concern:

Be it known that I, William Katz, a citizen of the United States of America, residing at Detroit, in the county of Wayne and State of Michigan, have invented a new, original, and ornamental Design for a Cup Hanger, of which the following is a specification, reference being had therein to the accompanying drawing, forming a part thereof, wherein:

Fig. 1 is a top plan view of a cup hanger, showing my new design;

Fig. 2 is a side elevational view thereof; and
Fig. 3 is a section taken on the line 3—3 of Fig. 1.

I claim:

The ornamental design for a cup hanger, substantially as shown.

WILLIAM KATZ.
